CLEANING MACHINE

James G. Hayward, Havertown, Pa.

Application February 3, 1949, Serial No. 74,381

7 Claims. (Cl. 299—141)

1
The present invention relates to cleaning devices, and more particularly to a cleaning device including a nozzle adapted to direct a stream of water under high pressure against the object to be cleaned. It relates more particularly to a cleaning device or machine adapted to remove scale, scum or film from the interior surfaces of tanks or bunkers in ships or railroad cars adapted to carry fuel oil, molasses or other fluid materials.

An object of the present invention is to provide a cleaning machine which forces a high pressure stream of cleaning fluid on all sides of the machine itself, without the necessity of rotating or twisting said cleaning device.

An additional object of the present invention is to provide a cleaning device or nozzle which has a self-contained rotating mechanism and which is adapted to direct a stream of cleaning fluid on all sides of said machine.

A further object of the present invention is to provide a cleaning device or nozzle which dispenses a sheet or sheets of cleaning fluid on all sides of said cleaning machine.

The above and other objects will appear more fully from the following description, drawings and claims.

For the purpose of illustrating the invention, there are shown in the accompanying drawings forms thereof which are at present preferred, although it is to be understood that the instrumentalities can be variously arranged and organized and that the invention is not limited to the precise arrangements and organizations of the instrumentalities as herein shown and described.

In the accompanying drawings, in which like reference characters indicate like parts.

Figure 1 represents a vertical cross-sectional view of one embodiment of the present invention.

Figure 2 represents a front elevational view, partly in section, of the embodiment shown in Figure 1.

Figure 3 represents a horizontal cross-sectional view generally along lines 3—3 of Figure 1.

Figure 4 represents a side elevational view of the embodiment shown in Figure 1, with the extreme positions of the movable element shown in dash-dot lines.

Figure 5 represents a cross-sectional view of the body of a sea-going vessel indicating how the embodiment of Figure 1 would be used to clean the interior surfaces of internal compartments of said vessel.

2
Figure 6 represents a vertical cross-sectional view of the fluid-motor of another embodiment of the present invention.

Figure 7 represents a vertical cross-sectional view of the embodiment of Figure 6, generally at right angles to the view shown in Figure 6.

Figure 8 represents a vertical cross-sectional view of a swivel-element adapted for use with the fluid-motor shown in Figures 6 and 7.

Figure 9 represents a vertical cross-sectional view like the view of the swivel-element shown in Figure 8, but with the ball-bearing rotated 90 degrees from the position shown in Figure 8.

Figure 10 represents a vertical cross-sectional view of the swivel-element of Figures 8 and 9, with the ball-bearing omitted therefrom for greater clarity, and taken at right angles to the views of Figures 8 and 9.

Figure 11 represents a horizontal cross-sectional view generally along lines 11—11 of Figure 9.

Figure 12 represents a vertical cross-sectional view through a modified form of swivel-element, adapted for use with the fluid-motor of Figures 6 and 7.

Figure 13 represents a side-elevational view of the nozzle-element of the present invention, and a support therefor, adapted for use in cleaning tubes or pipes such as boiler-tubes or the like.

Figure 14 represents a vertical cross-sectional view generally along lines 14—14 of Figure 13.

In the embodiment of the present invention shown in Figures 1—5 inclusive, there is shown a fluid-motor 20, a swivel-element 21 and a nozzle-element 22. These three elements are operatively connected so as to receive a stream of water, under pressure, through an inlet pipe 23, cause said stream of water to be directed against a paddle wheel 24 which transmits an oscillating motion to the nozzle-element 22, and thereafter direct said stream of water in one or more annular streams, generally radially from said nozzle-element 22.

The fluid-motor 20 consists of a housing 25 having a base 26 and a cover-plate 27. The cover-plate 27 has a threaded aperture 28 therein, adapted to receive the threaded end of the inlet pipe 23. A pair of guide-brackets 29 and 30 may be supported within the housing 25, or may be formed as an integral part of said housing 25.

The bottom 26 of the housing 25 has a threaded aperture therein adapted to receive a conduit 31 of the swivel-element 21, hereinafter to be described.

An inner chamber 32, defined by the walls of

the housing 25 and the support-brackets 29 and 30, is adapted to receive therein the paddle wheel 24. This paddle wheel 24 is mounted on a shaft 33 which is supported in bearing-holes 34 and 35. The paddle wheel 24 may be fastened to the shaft 33 by a tapered pin 33-a or by any other means.

One end 36 of the shaft 33 extends beyond the exterior surface of the housing member 25 and has a shoulder of reduced diameter adapted to receive a pinion or driving member 37. The pinion 37 may be fastened to the shaft 33 at the reduced portions 36 by a screw 38, or other means.

Near the lower end of housing 25 a boss or similar extension 39 is adapted to receive and support a bearing member 40 upon which a gear 41 may rotate. The gear 41 is enmeshed with the pinion 37 so that rotation of the paddle wheel 24 and pinion 37 will cause the gear 41 to rotate.

The gear 41 is adapted to receive a pivotable connecting member 42 to which is attached one end of a connecting rod 43 in a manner whereby the connecting rod 43 will be free to pivot in relation to the gear 41. This connection may be made through a ball-and-socket joint 44, or by any like means. The other end of said connecting rod 43 is pivotably attached to the nozzle element 22. When the gear 41 is caused to rotate by the paddle wheel 24, a swinging or pivoting motion is transmitted to said nozzle 22.

The swivel-element 21 consists generally of a ball 45 and a ball-receiving socket 46. The ball 45 may be fastened to the conduit 31, with a chamber or passage-way 47 therethrough. This chamber or passageway 47 permits the liquid delivered into the chamber 32 through the inlet pipe 23 to pass from the chamber 32 through the conduit 31 and the ball 45.

The socket member 46 may consist of a base 48 which is screw-threadedly attached to a cap 49. Bearing-rings 50 and 51 are supported in the cap and base 49 and 48 respectively so as to provide a fluid-tight seal in the swivel-element 21 and yet permit the ball 45 to rotate freely within the socket 46. A pin 52 may pass through the center of the ball 45 and the socket 46 so as to confine the movement of the socket 46 (and the nozzle 22 attached to the socket 46), to one plane, rather than to permit unlimited freedom of movement for said nozzle 22.

The base 48 of the swivel-element 21 may be perforated, as at 53, so as to permit the liquid delivered through passageway 47 to pass through and from the swivel-element 21.

At the lower end of the ball 45 the passageway 47 may be flared or beveled, as at 54, so that the aperture 53 may be in juxtaposition with the passageway 47 at various angular positions of the socket 46 with relation to the ball 45.

A threaded tube 55 having a flanged head 56 and a passageway 57 may be fastened to the base 48 of the socket 46, as by a number of bolts 58. The tube 55 is adapted to receive and support the various elements comprising the nozzle-member 22.

The nozzle-member 22 is adapted to dispense water away from and at an angle with the threaded tube 55. The top member or head 59 has an internally threaded orifice or aperture 60 by which it may be secured upon the threaded tube 55, somewhat below the flanged head 56. A lock nut 62 and a lock washer 63 are used to fasten the upper head 59 securely in position upon the threaded tube 55. The lock washer 63 may have an extension 64 terminating in a coupling 75.

member 65 adapted to receive the lower end of the connecting rod 43. This assembly permits the upper head 59 of the nozzle-member 22 to be adjusted axially along the threaded tube 55, and to be locked securely thereon. Moreover, the lock washer 63 with its coupler member 65 may be adjusted angularly so that the coupler 65 may be in operative position with respect to the connecting rod 43 when the lock nut 62 secures the lock washer 63 and the upper head 59 in position on the tube 55.

The head 59 has a conically-recessed under-surface 61. A baffle-plate 66 having upper and lower dished surfaces 67 and 68 respectively is secured upon the threaded tube 55 by a threaded aperture 69 and a lock nut 70. The baffle-plate 66 is spaced a short distance below the lower edge of the upper head 59 so that an annular orifice 71 is defined between the lower edge of the upper head and the upper edge of the baffle-plate 66. This provides a chamber 72 which is in communication with the passageway 57 through a number of perforations 73 in the threaded tube 55. The cleaning fluid flowing into the passageway 57 may thus pass through the apertures 73 into the chamber 72, thence outwardly through the annular orifice 71.

The baffle-plate 66 may be somewhat greater in diameter than the upper head 59 so that the outer edge of the baffle-plate 66 is beyond the outer edge of the upper head 59. This construction, in combination with the conical surface 61 of the upper head 59 and the dished surface 67 of the baffle plate 66 causes the annular stream of water to be directed outwardly and upwardly, at an acute angle with the axis of the threaded tube 55.

A lower deflector plate 74 is secured to the threaded tube 55 beneath the baffle-plate 66. This deflector 74 has an upper dished surface 75, and is supported on the tube 55 a slight distance beneath the baffle plate 66 as by the threaded opening 76 and a pair of tapered-lock-pins 77 (or similar fastening device such as a lock-nut or the like). This provides a lower annular orifice 78 and a lower diffusion chamber 79, similar to the upper diffusion chamber 72 and the upper orifice 71 heretofore described. A series of perforations 80 in the threaded tube 55 permit the cleaning fluid to pass from the passageway 57 into the diffusion chamber 79 and outwardly through the annular orifice 78. The lower deflection plate 74 is smaller in external diameter than the baffle plate 66 so that the annular stream of water will be deflected downwardly as well as outwardly, at an acute angle to the axis of the threaded tube 55 as well as at an angle to the first-mentioned stream of water emanating from the annular orifice 71.

The nozzle of my invention thus provides for the dispensing of cleaning fluid at an angle with the axis of the nozzle and on all sides of said nozzle. Moreover, I may place one or more perforations, such as the hole 81, in the terminal end of the threaded tube 55. This permits a stream or sheet of water to be dispensed beneath the nozzle 22 so that the surface directly beneath the cleaning machine may be effectively cleansed.

It is evident that the relative position of the upper head 59, and the baffle plate 66, and the deflection plate 74 may be adjusted axially along the threaded shaft 55. This affords a means for adjusting the size of the annular orifices 71 and 78. Thus, if I desire to use a stream of water emanating from the said orifices at a high velocity, I may adjust the various members so that the orifice-area is decreased. This also will permit

the streams of water to travel a greater distance and therefore clean a container of larger size than if the orifices were somewhat larger. Conversely, I may adjust the various members so that the orifices 71 and 78 have a somewhat greater area, thus providing for an increased flow of fluid at somewhat decreased velocity.

As heretofore described, the fluid-motor 20 transmits a rotary motion to the pinion 37 because the incoming stream of water passing through the inlet pipe 23 impinges against the paddle wheel 24. This rotary motion is transmitted to the gear 41 and to the pivot-member 42, causing the connecting rod 43 to oscillate in a more or less vertical direction. This upwardly-and-downwardly oscillating motion is transmitted to the bracket 65 on the lock washer 63 and thus to the nozzle element 22. Inasmuch as the nozzle element 22 is free to pivot about the swivel-element 21, a swinging or pendulum-like motion is transmitted to the nozzle 22. This operation is shown in Figure 4 wherein the center position of the nozzle is shown in solid lines whereas the extreme left and right positions of the nozzle are shown in the dash-and-dot lines, as at 25 82 and 83.

The oscillating motion of the nozzle 22 and the nozzle construction serve to direct the cleaning solution against all the internal surfaces of the compartment or bunker being cleaned. As is shown in Figure 4, by the schematic lines 84, the cleaning fluid will be directed against all the internal surfaces except the small area directly above the cleaning machine itself. However, the machine is generally lowered through an opening, such as the port hole 85 in a ship 86, and it is desirable that the water or cleaning solution does not splash upwardly through the port hole 85.

As is shown in Figures 6 and 7, I may use a fluid-motor wherein a rotary motion is imparted to an internal shaft 90, rather than to an external pinion 37 and gear 41 (as in the embodiment of Figure 1). The stream of liquid entering through the inlet pipe 23 may be directed against a paddle wheel 91 which rotates on a horizontal shaft 92. Attached to the paddle-wheel 91 is a worm 93, adapted to engage a gear 94 affixed to the shaft 90. This worm-and-gear assembly 93 and 94 functions as a speed-reducing agent so as to cause the shaft 90 to rotate at a greatly reduced speed with relation to the rotating paddle wheel 91. The shaft 92 may be supported in suitable bearings 95 and 96 in the housing 25 while the shaft 90 may be supported at its upper end in a suitable bearing 97, and beneath the gear 94 by a 50 spider-like bearing 98. The rotating vertical shaft 90 as well as the flow of cleaning fluid may thus pass through the conduit 31-a, and the internal passage-way 47 to the swivel-element disclosed in Figures 8-11. In Figures 6 and 7, the 60 housing 25 and the conduit 31-a are shown as integral members, however, these parts may be separate members.

Referring now to Figures 8-11 inclusive, I show a swivel-element (adapted for use with the fluid-motor disclosed in Figures 6 and 7) whereby an oscillating motion may be transmitted to the nozzle-element 22 by means fully-enclosed within the swivel-element.

The conduit 31-a may terminate in an upper hemispherical shell 100. A retainer 101 is adapted to be fastened to the shell 100, as by a number of bolts 102 passing through the flanges 103 and 104 on said retainer and shell members.

A ball-member 105 is adapted to fit within the 75

spherical internal surface of the shell 100, providing a fluid-tight joint between the ball 105 and the shell 100, and yet affording freedom of movement between these two parts. A pair of bearing pins 106 and 107 may be used to fasten the ball 105 to the shell 100 and permit motion about just one axis. An extension member 108 may depend from the ball 105, terminating in a flange 109 which is adapted to be secured to the flange 56 on the threaded tube 55, heretofore described. The bolts 58 may serve to fasten the flanges 56 and 109 together and to provide a fluid-tight seal between these two parts.

A pair of bearing-blocks 110 and 111 are pivoted 15 within the ball 105. These bearing-blocks support the outer race 112 of a ball-bearing member 113. The inner race 114 of the ball-bearing member 113 is securely fastened at an angle to the lower end of the rotating shaft 90, as by a hub 115. The inner race 114 of the ball-bearing member 113 is securely fastened to and rotates with the shaft 90.

The hub 115 is designed to support the ball-bearing member 113 at an angle with the axis of the shaft 90, as is more clearly shown in Figure 8. As the shaft 90 rotates, the outer edge of the inner race 114 of the ball-bearing member 113 travels through an undulating path. This undulating motion is, in turn, transmitted to the outer race, and particularly to that part of the outer race 112 which is fastened to the pivoted bearing-blocks 110 and 111. The bearing-blocks 110 and 111 (which are displaced 90 degrees from the pivot pins 106 and 107) oscillate about these said pivot pins and cause the ball-member 105 to swing about an axis drawn through the center lines of the pivot pins 106 and 107. This pivoting or oscillating motion is thus imparted to the conduit 108, which in turn causes the nozzle-member 22 to swing.

With reference to Figure 12, I show a modified form of swivel-element 120 consisting of a housing 121, a top cover 122 and a retaining-ring 123. A conduit 31-b has a flanged end 124 fastened to the top cover 122. The rotating shaft 90 passes through the conduit 31-b and supports, at its lower end, an angularly disposed ball-bearing member 113. The outer race 111 of the ball-bearing 45 113 is disposed in recesses 125 and 126 of a pair of sliding blocks 127 and 128 respectively. The blocks 127 and 128 oscillate within a number of guide-members 129 and 130 when the ball-bearing member 113 is rotated by the shaft 90. The oscillating motion of the guide blocks 128 and 127 is imparted to a ball-member 131, similar in construction to the ball-member 105 in Figures 8-11. A pair of connecting-rods 132 and 133 are pivotally supported in the blocks 127 and 128 and also in the ball-member 131. The ball-member 131 is supported by, and rotates in, a spherical groove formed partly in the lower end of the housing member 121 and partly in the retaining ring 123. The ball 131 may be secured to the housing member 121 and the retaining ring 123 by a pair of pivot pins similar to the pivot pins 106 and 107 on Figure 10. Thus, when the shaft 90 rotates, an oscillating motion is imparted to the sliding blocks 127 and 128 and to the ball-member 131, which swings back and forth about an axis concentric with the pivot pins 106 and 107. A conduit 134 having a flange at its lower end is a part of, or fastened to, the ball-member 131 so as to provide a support for the nozzle member 22.

With reference now to Figures 13 and 14, there

is shown a nozzle-member 22 having the threaded tube 55 and flanged end 56, without, and separated from, a fluid-motor 20 and a swivel-element 21. A more or less inflexible pipe 140 having a flanged end 141 is bolted or otherwise secured to the flange 56. In this manner, a non-oscillating nozzle 22 is provided which can be moved (horizontally or vertically) into a narrow chamber such as a boiler tube or the like, whereby to remove boiler-scale, scum, or other impurities from the inner surface thereof. It may provide a guide-bracket 142 so that the peripheral edge of the baffle plate 66 does not strike the surface of the boiler-tube or other container being cleaned. This bracket 142 may be fabricated from sheet-steel or wire or any other convenient material, and may consist of a side bracket 143 and a complementary side bracket 144, hooked together as at 145 and bolted together as by the bolts 146. This provides a guide surface 147 which supports the pipe 140 and the nozzle element 22, and permits the entire assembly to be moved along the inner surface of the boiler-tube.

The operation of the embodiment of my invention shown in Figures 1 and 2 is as follows: A supply of cleaning fluid, such as heated water or the like, is forced (under pressure) into the inlet pipe 23. This fluid strikes the blades of the paddle wheel 44 causing the shaft 33 and the pinion 37 (as well as the gear 41 enmeshed therewith) to rotate. The rotating motion is imparted to the bracket 42 and the connecting rod 43 oscillates in a more or less vertical direction. The oscillating motion of the connecting rod 43 is imparted, through the bracket 65 of the lock washer 63 to the nozzle-member 22, and the entire nozzle-assembly pivots about the pivot pin 52 in the center of the swivel-element 21. After the cleaning fluid has passed through the chamber 32 and the passage-way 47 it enters the passage-way 57 in the nozzle member 22. Thereafter some of it is forced out through the orifice 81 in a jet or sheet of fluid directly beneath the oscillating nozzle 22. The greatest quantity of the cleaning fluid passes through the apertures 73 and 80 into the diffusion chambers 72 and 79. This water is forced out through the annular orifices 71 and 78, more or less at an acute angle to the axis of the nozzle member 22. In this fashion, the spray of cleaning fluid is directed on all sides of the cleaning machine.

The operation of the embodiment of my invention shown in Figures 6-11 inclusive is as follows:

The cleaning fluid enters through the inlet pipe 23 and causes the paddle wheel 91 to turn the worm 93 and the gear 94 associated therewith. The rotation of the gear 94 is imparted to the vertical shaft 90 and to the ball-bearing member 113 fixed at an angle to the lower end of the shaft 90. The periphery of the ball-bearing member 113 travels through an undulating circle, causing the bearing-blocks 110 and 111 to oscillate up and down about the pivot pins 106 and 107. This oscillating motion is transmitted through the conduit 108 to the threaded tube 55 and the nozzle element 22. After the cleaning fluid has passed through the internal chamber of the housing member 25 it flows along the shaft 90 through the swivel-element 100, around the ball-bearing member 113 and through the conduit 108 into the diffusing chambers 72 and 79 of the nozzle element 22.

The operation of the cleaning machine embodying the swivel-element of Figure 12 is similar

to the operation of the machine embodying the fluid-motor and swivel-element of Figures 6-11 inclusive.

To provide a mechanism for cleaning boiler-tubes or the like, it is necessary only to disengage the nozzle-element 22 from the rest of the cleaning machine by removing the bolts 58 and separating the flange 56 from the bottom portion 48 of the ball-joint 21. Thereafter this flanged joint 56 may be fastened to the flanged joint 141 of a supply-pipe 140 (similar to the supply pipe 23). A supply of cleaning fluid is forced directly into the diffusion chambers 72 and 79 without first passing through a fluid-motor or a swivel-element. The guide-bracket 42 can be affixed to the pipe 140 and the entire assembly of nozzle-element 22 and supply pipe 140 can be slid horizontally (or vertically) into a small-diametered boiler-tube or the like.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, I claim as new and desire to protect by Letters Patent the following:

1. A nozzle including a pair of cup-shaped members spaced from and coaxially disposed with respect to each other, a baffle plate disposed between said cup-shaped members and a tubular support for rigidly and adjustably maintaining said cup-shaped members and said baffle plate in spaced relation to each other, the spaces intervening said cup-shaped members and said baffle plate being larger at the center than at the outer edges to form peripheral jet-outlets disposed generally radially of the nozzle and extending around the body of the nozzle, and at least one fluid-inlet in said tubular support in communication with the spaces between the cup-shaped members and the baffle plate, the said baffle plate and the said cup-shaped members on each side thereof being independently adjustable to vary the size of the peripheral outlets independently of each other.

2. A nozzle including a pair of cup-shaped members spaced from and coaxially disposed with respect to each other, a baffle plate disposed between said cup-shaped members and a tubular support for rigidly and adjustably maintaining said cup-shaped members and said baffle plate in spaced relation to each other, the spaces intervening said cup-shaped members and said baffle plate being larger at the center than at the outer edges to form peripheral jet-outlets disposed generally radially of the nozzle and extending around the body of the nozzle, and at least one fluid-inlet in said tubular support in communication with the spaces between the cup-shaped members and the baffle plate.

3. A nozzle including a pair of cup-shaped members spaced from and coaxially disposed with respect to each other, a baffle plate disposed between said cup-shaped members, and a tubular support for rigidly and adjustably maintaining said cup-shaped members and said baffle plate in spaced relation to each other, the spaces intervening said cup-shaped members and said baffle plate being larger at the center than at the outer edges to form peripheral jet-outlets disposed generally radially of the nozzle and extending

around the body of the nozzle, the peripheral edges of said baffle plate extending radially beyond the juxtaposed peripheral edges of said cup-shaped members, and a fluid-inlet in said tubular support in communication with the spaces between the cup-shaped members and the baffle plate.

4. A nozzle including a pair of cup-shaped members and a baffle plate disposed therebetween, said baffle plate and said cup-shaped members spaced from and coaxially disposed with respect to each other, a tubular support for rigidly and adjustably maintaining said cup-shaped members and said baffle plate in spaced relation to each other, the spaces between said cup-shaped members and said baffle plate being larger at the center than at the outer edges to form peripheral jet-outlets disposed generally radially of the nozzle and extending around the body of the nozzle whereby to permit discharge of a sheet of fluid from each of said peripheral jet-outlets substantially transversely to the axis of said cup-shaped members and said baffle plate, and a fluid-inlet in said tubular support in communication with the spaces between the baffle plate and the said cup-shaped members.

5. A nozzle including a tubular support and three nozzle-members secured thereto, two of said members being cup-shaped and one of said members being generally disc-like, said disc-like member and one of said cup-shaped members being movable on said tubular support, the other of said cup-shaped members being affixed relative thereto, said movable members being adjustable independently of said fixed member and of each other to provide a pair of independently adjustable jet-outlets, and radially-extending fluid-ports in said tubular support in communication with the spaces intervening said disc-like member and each of said cup-shaped members.

6. A nozzle including a tubular support and three nozzle-members secured thereto, two of said members being cup-shaped and one of said members being generally disc-like, said disc-like member and one of said cup-shaped members being movable on said tubular support, the other of said cup-shaped members being affixed relative thereto, said movable members being ad-

justable independently of said fixed member and of each other to provide a pair of independently adjustable jet-outlets, and radially-extending fluid-ports in said tubular support in communication with the spaces intervening said disc-like member and each of said cup-shaped members, said disc-like member being thinner at its center than at its periphery and the periphery of said disc-like member extending radially beyond the juxtaposed edges of each of said cup-shaped members.

7. A nozzle including a tubular support and three nozzle-members secured thereto, two of said members being cup-shaped and one of said members being generally disc-like, said disc-like member and one of said cup-shaped members being movable on said tubular support, the other of said cup-shaped members being affixed relative thereto, said movable members being adjustable independently of said fixed member and of each other to provide a pair of independently adjustable jet-outlets, and radially-extending fluid-ports in said tubular support in communication with the spaces intervening said disc-like member and each of said cup-shaped members, said disc-like member being thinner at its center than at its periphery and the periphery of said disc-like member extending radially beyond the juxtaposed edges of each of said cup-shaped members, and an orifice in the end of said tubular support, the area of said orifice being substantially smaller than the combined area of said radially extending fluid-ports.
